UNITED STATES PATENT OFFICE

149,510

DESIGN FOR A FINGER GUARD

Walter Meyer, Chicago, Ill.

Application May 5, 1947, Serial No. 138,815

Term of patent 7 years

(Cl. D74—1)

To all whom it may concern:

Be it known that I, Walter Meyer, a citizen of the United States, residing at Chicago, in the county of Cook and State of Illinois, have invented a new, original, and ornamental Design for a Finger Guard, of which the following is a specification, reference being had to the accompanying drawing, forming part thereof.

The design comprises a hollow member having two oppositely placed flaring enlargements on its exterior. It has a plurality of concentric raised members on its closed end and carries a raised portion within the concentric members.

I claim:

The ornamental design for a finger guard, as shown, and described.

WALTER MEYER.
